UNITED STATES PATENT OFFICE.

LEOPOLD KABIS, OF CHEYENNE, WYOMING, ADMINISTRATOR OF THOMAS MOORE, DECEASED.

DESIGN FOR A BUCKLE.

SPECIFICATION forming part of Design No. 29,278, dated August 30, 1898.

Application filed July 27, 1898. Serial No. 687,043. Term of patent 14 years.

To all whom it may concern:

Be it known that THOMAS MOORE, deceased, late a citizen of the United States, and a resident of Cheyenne, county of Laramie, and State of Wyoming, duly invented and produced a new and original Design for Buckles, of which the following is a full, clear, and exact description, reference being had to the accompanying drawing, forming a part thereof.

10 The figure is a plan view of a buckle embodying the new design.

As shown in the drawing, the leading or material feature of the design consists of a rectangular skeleton frame comprising the horizontally-arranged bar 1, a short horizontal bar 2, arranged parallel with the bar 1, the parallel vertical bars 3, extending from the ends of the bar 2 to the bar 1, and the bars 4, extending from the ends of the bar 2 at angles

20 of approximately forty-five degrees to the ends of the bar 1. A bar 5 extends between the vertical bars 3 at a point midway between the bars 1 and 2, said bar 5 being slightly larger in diameter than is the balance of the frame of the buckle, and extending from said 25 bar 5 to the bar 1 is a small bar 6, the same being midway between and parallel with the vertical bars 3.

What is claimed is—

The design for a buckle, substantially as 30 herein shown and described.

In testimony whereof I affix my signature in presence of two witnesses.

LEOPOLD KABIS,
Administrator of Thomas Moore, deceased.

Witnesses:

WALTER R. STOLL,
W.M. R. SCHNITGER.
